UNITED STATES PATENT OFFICE.

DAVID S. JACOBUS, OF JERSEY CITY, NEW JERSEY, ASSIGNOR TO THE BARCOCK & WILCOX COMPANY, OF BAYONNE, NEW JERSEY, A CORPORATION OF NEW JERSEY.

STEAM-BOILER.

1,280,745.

Specification of Letters Patent. Patented Oct. 8, 1918.

Application filed October 9, 1917. Serial No. 195,540.

To all whom it may concern:

Be it known that I, DAVID S. JACOBUS, a citizen of the United States, residing at Jersey City, in the county of Hudson and State of New Jersey, have invented certain new and useful Improvements in Steam-Boilers, of which the following is a specification.

My invention relates to steam boilers and more particularly to a water tube boiler of the Stirling type, and will be understood by reference to the accompanying drawings in which Figures 1, 2 and 3 are vertical longitudinal sections showing various modifications of the invention; Fig. 4 a section on the plane of the line 4—4 of Fig. 5 and on an enlarged scale; Fig. 5 a face view of one of the baffle plates of Fig. 4; Fig. 6 a section showing the relation of the baffle and yielding seal to the bridge wall and the mud drum; Fig. 7 a detailed sectional view of a tube clamp and gas seal; and Fig. 8 a top view and a section of a modified form of plate which may be used instead of the plates of Fig. 4. Similar reference numerals indicate similar parts in the several views.

Referring to Figs. 1, 4, 5 and 7, the boiler shown comprises three transverse steam and water drums 1, 2 and 3 connected by banks of tubes 4, 5 and 6 to a mud drum 7. I may use a single mud drum as shown, or a series of connected mud drums, and I intend to cover both constructions by the words lower chamber in the claims. The three upper drums must, however, be connected to this chamber whether it is in the form of one drum or several connected drums. The steam spaces of the front and middle upper drums are connected by circulators 8, and the steam spaces of the middle and rear upper drums are connected by circulators 9. The water spaces of the front and middle drums are connected by circulators 10 which support tiling 11, as shown. In this form there are no water circulators between the middle and rear upper drums. A baffle 12 is supported upon the second row of tubes of the front bank 4 and extends upwardly from a cross baffle 13 at the rear of the bridge wall 14. In the middle bank of tubes are two baffles 15 and 16, the former being at the front of the bank and extend-

ing downwardly from the middle steam and water drum, and the latter supported upon the rear row of tubes and extending upwardly from the mud drum, these baffles being so arranged as to provide an up-pass for the gases in the middle bank. A cross baffle 17 is supported upon tube clamps between the front and middle banks at the lower end of the baffle 15. A cross baffle or shelf 18 extends from the baffle 16 toward the rear bank of tubes. The gases flow upwardly along the tubes in front of baffle 12, crossing the front bank of tubes at the upper end thereof, thence in a general downward direction along and among the tubes at the rear of baffle 12, thence upwardly along the tubes of the middle bank, and finally downward among the tubes of the rear bank to the outlet flue 19.

By placing the baffle 12, which comes nearest the fire, back of the second or third row of tubes, I am enabled to maintain a lower furnace temperature than would exist by placing said baffle back of the first line of tubes. The boiler is shown as fired by an underfeed stoker 20, the baffle arrangement described being particularly adapted to that type of stoker by reason of the fact that it is operated by a forced blast and produces a high furnace temperature. The arrangement is also adapted to other types of stokers and its use is not limited to underfeed stokers.

By employing the cross baffle 13 I am enabled to make use of a dust pocket 14' at the rear of the bridge wall 14. The opening 13' is left between the baffle 13 and the mud drum and the soot and ashes which are deposited from the gases fall through the opening 13' into the dust pocket 14'.

If desired, a superheater may be placed in the triangular space between the front and middle banks of tubes. In the form shown in Fig. 1 the superheater comprises the boxes 21 and 22 to which the upwardly extending U tubes 23 are connected. The boxes are supported in saddles resting upon the cross beam 24 forming part of the structural work of the setting. The tubes 23 extend substantially parallel with the tubes of the middle bank. Clamps secured to the front row of tubes of the middle bank serve as supports for resisting the overturning mo-

ment of the superheater. In the steam space of the middle upper drum is a dry pipe 25 from which the steam is delivered to the main 26 leading to the inlet superheater box 21.

A feed pipe 27 enters the rear drum 3 and discharges into a trough 28 from which trough the water is distributed longitudinally in the drum.

10 Direct impingement of the gases upon the rear steam and water drum, and protection of the butt-straps 29 and 30 is afforded by a special baffle 31 extending from the middle steam and water drum at a point below the 15 butt-strap 29, to substantially the underside of the rear upper drum below the butt-strap 30. This baffle is preferably of cast iron, made up in sections, and supported from above by rods 32.

20 In Fig. 2 I have shown a modified arrangement in which the baffle 12 is supported upon the third row of tubes of the front bank. Also, I have provided a baffle 34 for the rear bank of tubes extending downwardly from 25 the rear upper drum so as to give a down-pass for the gases after they leave the middle bank of tubes, and an up-pass at the rear of baffle 34 to the outlet flue 35. In this form I have omitted the cross baffles 17 and 18, 30 and also the superheater of Fig. 1. I prefer, however, in this form, with the baffle 12 supported upon the third row of tubes of the front bank, to use an arch 36 extending from the front wall of the setting above the 35 stoker.

In Fig. 3 I have shown the same baffling for the front and middle banks of tubes as in Fig. 1 except that I have omitted the cross baffle 17. I provide the rear bank with 40 a baffle 37 so that the gases after flowing downwardly over the tubes of the rear bank flow upwardly back of the rear bank to the flue outlet 35. In this form all of the steam is delivered to the rear upper drum 3 from 45 which it is taken through the steam main 38 to the superheater.

In Figs. 4 to 7 I have shown the details of a special baffle and yielding seal between the lower end of the baffle 12 and bridge wall 14. 50 This baffle is made up of cast iron plates 38 fitted around the tubes from side to side of the boiler with sufficient clearance to permit of their ready installation and to permit tubes being removed without disturbing 55 the baffle. The inner ends of the plates 38 rest upon an angle iron 39 supported by the front ends of the tube clamps 40 upon which the baffle 12 rests. The outer ends of the plates 38 rest upon clamps 41 upon the 60 first row of tubes of bank 4. The ends of the plates 38 which bear on the clamps 41 are made of such a form that the front line of boiler tubes may be removed without removing the plates 38. In case a tube in the second line has to be removed the clamps 41

in front of the tube can be removed as well as the plates 38 which surround the tube and the tube can be removed and replaced without disturbing the baffle 12. A layer of ganister and fire clay or similar material 42, applied in a plastic state upon the plates 38, serves to protect them and affords a gas tight seal. The clamps 41 are formed with a lip, as shown in Figs. 6 and 7, upon which rests, at one end, a series of overlapping plates 43. These overlapping plates are an improvement on those shown and described in my application Serial 55,771, filed Oct. 14th, '15, for steam boilers, in which application the plates were not made to 70 overlap. The overlapping of the plates is an important element in securing tightness, as the dust and soot which collects on the plates will become firmly embedded between the overlapped plates thus leading to a much 75 tighter seal than is secured where the plates simply abut at their edges. The other end of these plates rests upon bridge wall 14, the plates as a whole forming a yielding seal which allows relative movement between the 80 seal and the bridge wall without destroying the seal. In addition to this seal I may also introduce a similar seal 45 between the mud drum 7 and the floor, as shown in Figs. 1, 2 and 3. These seals are described in my 85 application, Serial No. 55,771 filed October 14, 1915.

In Fig. 8 I have shown overlapping plates 46 which may be used instead of the plates 38 for the baffle between the lower end of 90 baffle 12 and the yielding seal.

What I claim and desire to secure by Letters Patent of the United States is:—

1. A steam boiler comprising a bank of generating tubes, upper and lower drums 105 into which said tubes are expanded, a longitudinal baffle in said bank to direct the course of the gases, a furnace having a bridge wall, a cross baffle extending from said longitudinal baffle, and a yielding seal 110 between said cross baffle and said bridge wall.

2. A steam boiler comprising a bank of generating tubes, upper and lower drums 115 into which said tubes are expanded, a longitudinal baffle in said bank to direct the course of the gases across said bank at the upper part thereof, a furnace having a bridge wall, a cross baffle extending from said longitudinal baffle, a yielding seal between 120 said baffle and bridge wall, and a dust pocket in the rear of the bridge wall below said cross baffle and seal.

3. A steam boiler comprising a bank of generating tubes, upper and lower drums 125 into which said tubes are expanded, a longitudinal baffle to direct the course of the gases across said bank at the upper part thereof, a furnace bridge wall in front of said lower drum, a cross baffle extending 130

from said longitudinal baffle, and a yielding seal between said cross baffle and said bridge wall.

bridge wall below said cross baffle, said cross baffle being so arranged that it can be removed and replaced either in whole or in
